UNITED STATES PATENT OFFICE

136,615

DESIGN FOR A BABY'S SHOE

Gertrude Crawford, Mattoon, Ill.

Application September 9, 1943, Serial No. 111,080

Term of patent 7 years

To all whom it may concern:

Be it known that I, Gertrude Crawford, a citizen of the United States, residing at Mattoon, in the county of Coles and State of Illinois, have invented a new, original, and ornamental Design for a Baby's Shoe, of which the following is a specification, reference being had to the accompanying drawing, forming part thereof.

The figure is a perspective view of a baby's shoe showing my new design, the opposite side presenting substantially the same appearance as the side shown.

I claim:

The ornamental design for a baby's shoe, as shown and described.

GERTRUDE CRAWFORD.
